UNITED STATES PATENT OFFICE.

JAMES M. SHERMAN, OF DALLAS, TEXAS.

PUMP.

REISSUED

1,143,325.

Patented June 15, 1915.

Specification of Letters Patent. Application filed November 21, 1913. Serial No. 802,184.

To all whom it may concern:

Be it known that I, JAMES M. SHERMAN, citizen of the United States, residing at Dallas, in the county of Dallas and State of Texas, have invented certain new and useful 5 Improvements in Pumps, of which the following is a specification.

My invention relates to a new and useful pump, and its object is to provide a pump 10 that will eliminate intake and discharge valves by employing two pistons each having its own cycle of reciprocating motion.

The object more specifically stated is to 15 provide a pump, comprising two pistons mounted to reciprocate independently in a single barrel, one of said pistons serving to draw fluid into the barrel while moving in a certain direction, and the other serving to discharge said fluid while later following 20 the first one, the return strokes of the two pistons being simultaneous.

Finally, the object of my invention is to 25 provide a device of the character described that will be strong, durable, efficient and simple and comparatively inexpensive to produce, also one in which the several parts will not be likely to get out of working order.

With these and other objects in view, the 30 invention has relation to certain novel features of construction and operation, an example of which is described in the following specification and illustrated in the accompanying drawing, wherein:

35 Figure 1 is a view showing my novel pump in side elevation, showing the positions, occupied by the pistons, just after they have completed their return strokes. Fig. 2 is a longitudinal vertical sectional view of the same. Fig. 3 is a transverse vertical sectional view taken upon the line $x-x$ of Fig. 1. Fig. 4 is a transverse vertical sectional view taken upon the line $y-y$ of Fig. 1. Fig. 5 is a transverse, vertical 40 sectional view taken upon the line $z-z$ of Fig. 1. Figs. 6 and 7 are respectively surface developments of two cylindrical cams which in my invention respectively actuate the reciprocation of the two pistons.

45 Referring now more particularly to the drawings, wherein like reference characters designate similar parts in all the figures, the numeral 1 denotes the barrel of my pump, which is preferably mounted horizontally, and is held spaced above a platform 2, by one or more legs 3. Adjacent to

its extremities the barrel 1 is formed with annular chambers 4, communicating with the barrel interior through ports 5. With the chambers 4, intake and discharge pipes 6 and 7 respectively have communication. 60

Within the intake and discharge end portions of the cylinder 1, there are respectively mounted similar elongated pistons 8 and 8^a, each preferably carrying one or more packing-rings 9 upon its inner end. From the outer ends of the two pistons, alined rods 10 are rigidly extended in opposite directions. Upon the rods 10, there are loosely mounted elongated sleeves 11 of square cross-section, terminating at their outer ends flush with the outer ends of the rods 10, and received at said ends in brackets 12 respectively mounted upon the extremities of the platform 2. The apertures in the brackets 12 receiving the sleeves 11 are of square shape, permitting sliding displacement of said sleeves relative to the correlated brackets, but restricting the sleeves against rotation. In order to produce a unity of sliding 70 displacement between each sleeve 11 and the correlated rod 10, without restricting the latter member from rotation independent of the former, a set-collar 14 is mounted fast upon each rod 10, contiguous with the inner extremity of the correlated sleeve 11, and is recessed within a square casing 15 bolted fast to said sleeve. 80

The brackets 12 are extended above the sleeves 11 to form bearings for the extremities of a shaft 16, parallel to the axis of the barrel 1, and spaced above said barrel, a driving-pulley 17 being mounted fast upon said shaft. Adjacent to the ends of the shaft 16, there are respectively mounted 90 cylindrical cams 18 and 19, which respectively carry continuous curved threads 20 and 21, each engaging between a pair of lugs 22 formed integrally upon the adjacent sleeve 11. 95

An explanation of the operation of the above-described device will now be given. To start with, it may be considered that the various parts occupy the positions, shown in Figs. 1, 2, 3, 4 and 5. During the first third 100 of a revolution, the cam 18 will actuate the piston 8^a forwardly through a complete stroke, displacing said piston to the position shown in Fig. 2^a. The piston 8 will remain stationary until the other piston is completing its stroke, so that the space vacated by the piston 8^a may fill with a fluid entering 105

through the pipe 6 and correlated chamber 4 and ports 5. The piston 8 will start forward just in time to close the intake ports 5 before the discharge ports 5 are opened, so that just after the piston 8^a has completed its forward stroke, the piston 8 will occupy the position shown in Fig. 2^a.

During the time that the cams 18 and 19 are undergoing the second third of a revolution, the piston 8^a remains stationary and the piston 8 moves steadily forward, forcing the fluid through the discharge ports 5 and chamber 4 into the pipe 7. After having completed its forward stroke, the piston 8 will be either in contact with or very closely adjacent to the piston 8^a. While the cams 18 and 19 are completing the last third of a revolution, the relation between the pistons 8 and 8^a just described remains the same, the rearward strokes of the two pistons being simultaneously accomplished. The developments of the two cam surfaces shown in Figs. 6 and 7 give a clear idea of the manner in which the proper relative positions of the pistons are at all times maintained during a revolution of the cams.

By eliminating valves from the above-described pump, the cost of constructing the same is reduced and the operation is so simplified as to make repairs very infrequent and obviate a considerable part of the attention required by most pumps.

While it is preferred to drive my pump

by means of cams as illustrated and described herein, it is to be understood that other drive mechanisms may be employed to produce the same piston motions. My invention is presented, therefore, as including all such modifications and changes, as properly come within the scope of the following claims:

What I claim is:

A pump, comprising a barrel, having inlet and outlet ports adjacent to its extremities, two pistons mounted to reciprocate independently in said barrel, aligned rods oppositely projecting from each piston, sleeves within which said rods are free to rotate, means for causing a simultaneous sliding movement of the rods and sleeves, means slidably supporting said sleeves and restricting the same against rotation, and cams, respectively engaging said sleeves, for causing a reciprocating motion of the two pistons such that one moves forward while the other remains stationary, the other then moving forward while the first one remains stationary, the two undergoing their return stroke in unison.

In testimony whereof I have signed my name to this specification in the presence of two subscribing witnesses.

JAMES M. SHERMAN.
